Primary Examiner — Angela J Lee(74) *Attorney, Agent, or Firm* — Morgan, Lewis & Bockius LLP(57) **CLAIM**

The ornamental design for a television receiver with graphical user interface, as shown and described.

DESCRIPTION

FIG. 1 is a front, right side, perspective view of a television receiver with graphical user interface showing our new design;

FIG. 2 is a front view thereof; and,

FIG. 3 is a view of the graphical user interface.

The broken lines shown in the drawings represent portions of the television receiver that form no part of the claimed design.
